UNITED STATES PATENT OFFICE.

JOSEPH W. HOPKINS, OF NEW YORK, N. Y., ASSIGNOR TO HIMSELF, ALBERT G. BEARUP, AND PATRICK CARRAHER, JR., OF SAME PLACE.

IMPROVEMENT IN VALVES FOR STEAM-ENGINES.

Specification forming part of Letters Patent No. 123,174, dated January 30, 1872.

To all whom it may concern:

Be it known that I, JOSEPH W. HOPKINS, of the city, county, and State of New York, have invented a new and useful Improvement in Valves for Steam-Engines; and I do hereby declare that the following is a full, clear, and exact description of the same, reference being had to the accompanying drawing forming part of this specification, and in which—

Figure 1 represents a longitudinal sectional elevation of a valve constructed in accordance with my improvement, and Fig. 2 a transverse vertical section of the same.

Similar letters of reference indicate corresponding parts in both figures.

This invention consists in the combination, within a valve or steam-chest, of an oscillating abutment and a slide-valve with attached cylinder, the abutment being arranged within the cylinder, and being provided with inlets and outlets for operation in concert with passages in the slide-valve and with the ports or passages of the engine-cylinder so that, on turning the abutment at intervals alternately in a reverse direction, steam is admitted to and exhausted from opposite ends alternately of the valve-cylinder to throw the valve. Said improvement is applicable to steam-pumps as well as to steam-engines.

Referring to the accompanying drawing, A represents the valve or steam-chest of an engine, and *a* its steam-inlet. B is the valve-seat, having an exhaust-passage, *b*, and the usual ports or passages *c c'* leading to opposite ends of the engine-cylinder. C is the slide-valve, arranged to work over and control said passages. This valve is of a D-shaped construction, being provided with a central exhaust-cavity, *d*, and end steam-inlets or passages *e e'*. Attached to the back of said valve is a cylinder, D, having a steam-inlet, *f*, in its rear. Within this cylinder is a piston-like abutment, E, hung so as to be capable of being turned about its axis and that of the cylinder which it fits by means of a rod, *g*, but having no motion in direction of the length of the cylinder. Said abutment is provided on its one side, in proximity to the inlet *f* in

the valve-cylinder, with passages *h h'*, arranged to open into or through said side of the abutment at points occupying a spiral relation around the abutment, and communicating in a cross manner with the ends of the latter. The opposite side of the abutment is also provided at its ends with ports or passages *i i'*, arranged out of line with each other, and operating in concert with branch openings *k k'* passing through the back of the slide-valve and connecting with the exhaust-cavity *d* in the latter.

The operation is as follows: Every time the engine-piston approaches the ends of its stroke in opposite directions it communicates, by means of a tappet motion or otherwise, a circular movement in a given direction about its axis to the abutment E, causing one or other passages *h h'* to be brought into communication with the opening *f*, so as to pass steam to one end of the abutment E and so act upon the cylinder D as to cause the valve C to be thrown to the right or to the left, and thus put the ports *c c'* in communication, respectively, with the steam-chest A and exhaust-passage *b*. During such movement of the valve, and after it has been fairly started, the opening *f* passes beyond the passage *h* or *h'* and shuts off steam. The reverse movement of the valve is effected by turning the abutment E in a reverse direction so as to bring the other one of the passages *h* or *h'* in communication with the opening *f*, and one of the exhaust-ports *i* or *i'* in communication with its exhaust-branch *k* or *k'*, so as to free the one end of the cylinder D of steam and admit it to the opposite, the ports *i i'* operating alternately every throw of the valve. The arrangement is such that as, in the movement of the cylinder D, steam is cut off from either of the passages *h h'* by the opening *f* passing beyond them the corresponding exhaust-port *i* or *i'* is also cut off from communication with the passages *k k'*, thereby producing a cushioning action of the cylinder. Means may be provided, if desired, for regulating the period of thus cutting off the steam and exhaust-passages *h h'* and *i i'*, or either.

This constitutes a very simple, quick, and efficient valve.

What is here claimed, and desired to be secured by Letters Patent, is—

The combination of the oscillating abutment E with a slide-valve, C, having an attached cylinder, D, surrounding said abutment, and ports for passages establishing com-

munication between said cylinder, valve-chest A, and ports or passages in connection with the engine-cylinder, substantially as specified.

JOSEPH W. HOPKINS.
